ALMON L. BRAINARD.

UNITED STATES PATENT OFFICE.

ALMON L. BRAINARD, OF ONEIDA, NEW YORK.

DESIGN FOR A FAN.

SPECIFICATION forming part of Design No. 17,703, dated September 13, 1887.

Application filed June 28, 1887. Serial No. 242,830. Term of patent 7 years.

To all whom it may concern:

Be it known that I, ALMON L. BRAINARD, of Oneida, in the county of Madison, in the State of New York, have invented a new and useful Design for Fans, of which the following, taken in connection with the accompanying photographic illustrations, is a full, clear, and exact description.

The leading feature of my design consists of a fringed border, a central disk and lace-work ground surrounding said disk, and a bouquet or other ornament in the center of the central disk, with a scalloped strip surrounding the lace-work.

The letter *a* indicates the fringed border; *c*, the central disk; *l*, the lace-work ground; *b*, the bouquet, and *c* the scalloped edges of the central disk.

I claim—

The design for a fan, consisting of the fringed border *a*, the central disk, *c*, the lace-work ground *l*, the bouquet *b*, and the scalloped edges *c*, the whole forming a series of ornaments bearing the relation to each other substantially as described and shown. 20 25

In testimony whereof I have hereunto signed my name and affixed my seal, in the presence of two attesting witnesses, at Oneida, in the county of Madison, in the State of New York, this 16th day of June, 1887.

ALMON L. BRAINARD. [L. S.]
